CONTOURED PILLOW

Robert L. Howe and Norma C. Howe, both of 4581 Park-ridge Road, Sacramento, Calif. 95822

Filed Aug. 4, 1969, Ser. No. 18,525

Term of patent 14 years

Int. Cl. D28—99

U.S. Cl. D83—1

FIG. 1

FIG. 2

FIG. 3

FIG. 4

FIG. 5

FIG. 6

FIG. 7

FIG. 1 is a top plan view of a contoured pillow showing our new design;

FIG. 2 is a bottom plan view;

FIG. 3 is an elevational view of one side, the opposite side being substantially similar in appearance;

FIG. 4 is a rear elevational view;

FIG. 5 is a front elevational view;

FIG. 6 is a perspective view; and

FIG. 7 is a fragmentary sectional view, to an enlarged scale, the plane of the section being indicated by the line 7-7 in FIG. 1.

We claim:

The ornamental design for a contoured pillow, as shown and described.
